UNITED STATES PATENT OFFICE.

ELMER J. POURMON, OF NEWARK, NEW JERSEY.

DESIGN FOR A CURTAIN-SHADE BRACKET.

Application filed May 27, 1921. Serial No. 473,157. Term of patent 3½ years.

To all whom it may concern:

Be it known that I, ELMER J. POURMON, a citizen of the United States, residing at Newark, in the county of Essex and State of New Jersey, have invented a new, original, and ornamental Design for a Curtain-Shade Bracket, of which the following is a specification, reference being had to the accompanying drawing, forming part thereof.

In the drawings:—

Figure 1 is a side view of my new curtain shade bracket.

Figure 2 is an edge view of the same.

I claim:—

The ornamental design for a curtain shade bracket as shown.

ELMER J. POURMON.
